UNITED STATES PATENT OFFICE.

ABRAM PLOTKIN, OF BROOKLYN, NEW YORK.

AUTOMOBILE-CAP.

1,084,109.

Specification of Letters Patent.

Patented Jan. 13, 1914.

Application filed February 12, 1913. Serial No. 747,841.

To all whom it may concern:

Be it known that I, ABRAM PLOTKIN, a subject of the Czar of Russia, residing at Brooklyn, county of Kings, and State of New York, have invented a new and Improved Automobile-Cap, of which the following is a specification.

This invention relates to an automobile cap more particularly adapted to be worn by ladies and which effectively protects the face of the wearer from the elements, shields the eyes from dust and wind, and prevents the hair from bagging over the forehead.

In the accompanying drawing: Figure 1 is a perspective view showing my automobile cap in use; Fig. 2 a similar view with the vizor folded into the cap; Fig. 3 a view similar to Fig. 2, showing a modification of the cap; Fig. 4 a side view of the cap shown in Figs. 1 and 2; Fig. 5 a front view thereof; Fig. 6 a vertical section thereof; Fig. 7 a perspective view of the cap shown in Fig. 3, and Fig. 8 a detail showing the rear shirring string.

The body 10 of the cap is made in the form of a shallow bonnet or hood adapted to fit the head of the wearer. At its front, the hood is gathered into fixed rearwardly extending folds 11, so as to be somewhat expansible and accommodate the front hair. To the front edge of the hood, there is secured a vizor 12 made of flexible material and adapted to be folded either outward at an obtuse angle so as to project over the forehead (Fig. 1), or inward so as to be turned into the crown against the lower side of the hood (Fig. 2) and thus leave the face exposed. Vizor 12 is provided with a lower central notch 13 to fit the nose, and with a pair of windows 14 for the eyes, so that the use of separate goggles is dispensed with. Each window is covered at its edge by a flexible and preferably overspun oval frame 15 which here reinforces and stiffens the vizor. Over the front of the hood directly back of the vizor, there extends from side to side, a transverse band 16, which is attached to the hood along its forward edge, but is disconnected therefrom at its rear edge. At its ends, the band may likewise be sewn to the hood and be here provided with ornamental buttons 17

as shown. The band will cover up the forward portions of the folds 11 and thus 55 while the latter may expand in conformity to the style of the coiffure, the expanded folds will be prevented from producing an unsightly bagging effect above the vizor, the forward edge of the band serving at 60 the same time for holding the hair back from the forehead.

At the neck or lower edge, the hood is provided with an elastic shirring string 18, (Fig. 8) which here draws the hood together into back folds 19. This elastic shirring string by gathering in the cap at the back, has the important function of tending to contract the cap at its front edge and to thus tightly draw the vizor 12 70 against the forehead, so that dust or wind cannot creep in under the same.

From the shirred back of the hood, there depends the rear section of a neck piece or cape 20, which is extended some distance 75 beyond one side of the hood, so that it may be folded with its loose end over the shoulders. This cape carries one member 21 of a fastener, the other coacting member 22 of which is carried by the other side of the 80 hood.

After the cap has been placed on the head, the loose end of the cape is drawn across the front of the neck, the fasteners 21, 22 are closed, and then the cape is 85 thrown over the shoulders, so that the wearer is thoroughly protected.

With the modification shown in Figs. 3 and 7, the cape 20 is omitted, but otherwise the cap is of the same construction as that 90 shown in the other figures.

I claim:

An automobile cap comprising a hood, having a gathered front to form a plurality of rearwardly extending folds, a windowed 95 vizor foldably secured to said front, and a band extending transversely over the hood and connected at its forward edge to the front thereof directly back of the vizor, while the rear edge of the band is disconnected from the hood to form an expansile 100 but covered hood-section back of the vizor.

ABRAM PLOTKIN.
